UNITED STATES PATENT OFFICE.

ROBERT L. MCKINNEY, OF PITTSBURGH, PENNSYLVANIA.

DOOR LATCH.

Application filed June 21, 1924. Serial No. 721,536.

To all whom it may concern:

Be it known that I, ROBERT L. MCKINNEY, a citizen of the United States, and resident of Pittsburgh, in the county of Allegheny and State of Pennsylvania, have invented 5 a new and useful Improvement in Door Latches; and I do hereby declare the following to be a full, clear, and exact description thereof.

10 My invention relates to door latches of somewhat the usual form, operable from either side of the door, but containing certain improvements.

One object of my invention is to provide 15 a latch which automatically adjusts itself to fit doors of varying thickness when being applied thereto.

Another object of my invention is to provide 20 an arrangement whereby an ordinary lifting latch may be actuated from either side of the door, by the hand of the operator as he grasps one of the pull handles to open the door.

Still another object of my invention is to 25 simplify and improve generally the structure and arrangement of door latches.

One form which my invention may take 30 is shown in the accompanying drawing wherein Fig. 1 is a perspective view of a door to which my latch is applied; Fig. 2 is a sectional edge elevational view of the apparatus of Fig. 1; Fig. 3 is an enlarged detail view of latch bar and form of lifting pin which I employ, and Fig. 4 is an enlarged detail view of the thumb lever shown 35 in the Fig. 2.

My latch is shown as applied to a door 5 which may be of any desired thickness. The usual pull handles 6 and 7 are provided 40 for moving the door, and a latch-bar 8 is pivotally supported on the door at 9 which moves within the usual slotted member 10. A catch 11 is secured to the door-frame 12. The parts thus far enumerated may be of 45 substantially the usual form.

A lifting pin 13 is rigidly secured to the latch 8 and has a shank portion extending into a hole 14 which extends through the door.

50 A thumb lever 15 is pivotally supported by the handle 7 in a well known manner, but instead of extending to a point beneath the latch 8, is provided with an upturned recessed portion 16 that engages the under 55 side of the pin 13.

In the usual form of simple latches a

thumb-lever extends from the outer side of the door clear through to the inner side thereof and is pivoted intermediate its ends. The inner end of such levers are downwardly bent in the form of a hook. When opening such doors from the outside, the thumb of the operator is simply pressed against the flat portion of the thumb-lever, but to unlatch the door from the inside, he 60 places his hand beneath the hook-portion to raise it, and at the same time exerts a pull thereon to swing the door open. This latter feature is objectionable in the case of heavy doors because of the limited grasp 65 which it is possible to secure on the hook portion of the lifting lever. Furthermore, the old form of latch referred to is not readily adaptable to doors of varying thickness. 70

By my invention both these objections are 75 overcome. The slideable engagement between the thumb-lever 15 and the inner end of the pin 13 permits these parts to assume relative operative positions regardless of the thickness of the door to which the latch 80 mechanism is applied, as will be apparent from an inspection of Fig. 2. The disposition of the handle 6 directly in front of the outer end of the pin 13 permits the underside of this pin to be engaged by the 85 upper side of the first finger of the operator when he is in the act of grasping the handle 6 to pull the door open. As above stated, this latter feature is particularly useful in the case of heavy doors where a great deal 90 of force is required to move them, and avoids the necessity of employing one hand to lift a latch and another hand to grasp a pull-handle to swing the door.

Various changes in detail may be made 95 without departing from the spirit and scope of the invention as defined in accompanying claims.

What I claim is:

1. Door latching mechanism comprising 100 a thumb-lever pivotally supported adjacent to the front of the door and extending rearwardly, a latch pivotally supported at the rear side of the door, and a pin carried by the latch and extending forwardly of the 105 door, the said pin and thumb-lever having telescopic engagement and being of such length that their adjacent ends do not protrude at the sides of the door.

2. Door latch mechanism comprising a 110 handle at the front side of the door, a lever pivotally supported adjacent to said handle

- and extending rearwardly, a latch adjacent to the rear side of said door, a lifting pin secured to said latch and extending forwardly therefrom, and means comprising a 5 V-shaped projection on said thumb-lever for raising said pin, the V-shaped projection and the forward end of the lifting pin terminating at points intermediate the sides of the door.
- 10 3. Door latching mechanism comprising a latch, a projection carried by said latch and extending rearwardly therefrom, and a handle secured to the said door and hav-

ing a hand-engaging portion disposed opposite to the end of said projection. 15

4. Door latching mechanism comprising a latch, a lifting pin carried by and extending forwardly and rearwardly of said latch, and a lever positioned adjacent to the forward end of said pin and having 20 connection therewith, the said lever and the rear end of said pin serving as lifting devices for said latch.

In testimony whereof I, the said ROBERT L. MCKINNEY, have hereunto set my hand.

ROBERT L. MCKINNEY.
